UNITED STATES PATENT OFFICE

ROLAND P. PLACE, OF MIDLAND, MICHIGAN, ASSIGNOR TO ROLAND P. PLACE CO., OF MIDLAND, MICHIGAN, A CORPORATION OF MICHIGAN

COMBINATION DRESSING AND GRINDING WHEEL

Application filed July 2, 1928. Serial No. 289,773.

This invention relates to cutting and abrading wheels and the like, and particularly to a combination tool for dressing a grinding wheel as it is rotated.

5 The prime object of the invention is to design a combination cutting and abrading tool so constructed as to dress the wheel that grinds the work, and in which the hardness and area of the cutting element regulates the 10 grinding action.

Another object is to provide a simple, substantial, and inexpensive dressing tool, which is of simple construction, and in which the abrasive material is tightly held.

15 A further object is to provide a combination dressing tool, which will eliminate one dressing operation, which will wear evenly, and which can be formed of any desired density or hardness.

20 The above and other objects will appear as the specification progresses, reference being had to the accompanying drawings in which I have shown the preferred embodiment of my invention, and in which like reference numerals indicate like parts throughout the several views thereof.

In the drawings:

Fig. 1 is a section of my combination dressing and abrading wheel taken on the line 30 1—1 of Fig. 2.

Fig. 2 is a vertical transverse view taken on the line 2—2 of Fig. 1.

Fig. 3 is a side view of the tool.

Fig. 4 is an edge view of the nut and locking washer.

Fig. 5 is an end view thereof.

Heretofore when a grinding wheel becomes unfit for accurate service it has been customary to first dress said wheel by means of a tool provided with a plurality of hardened toothed cutters which are rotated by contact therewith, an abrading tool being then used to finish and smooth to proper size and smoothness. This necessitated two distinct and separate operations, and I have therefore perfected a combination tool which simultaneously dresses and grinds the wheel, the dressing action being governed by the hardness and spacing of the dressing cutters and the density of the abrading material.

Referring now to the drawings in which I have shown the preferred embodiment of my invention, the numeral 5 indicates a preferably hood shaped case in which the cutting and abrading element is rotatably mounted, 55 a handle 6 being secured thereto, or can be formed integral therewith if desired. Hubs 7 and 8 respectively are formed on opposite sides of the case, and are split as shown at 9 to permit the entire cutting and abrading element to be removed as a unit, all as shown and described in my application for Letters Patent for dressing tools filed July 1, 1927, Serial No. 202,911 and I shall not describe the specific mounting of the unit in detail, as it comprises no part of the present invention, which is directed to the combination and construction of the cutting and abrading unit, excepting that the unit is mounted on a shaft 10, 60 suitably secured in the hubs 7 and 8, said shaft having spaced apart bearing assemblies 11 and 12 mounted thereon, and on which the hollow tubular barrel member 13 is mounted, the ends of said barrel being counterbored as shown at 14 to accommodate said bearings. 65

The outer surface of the barrel is turned as shown at 15 to form a shoulder 16 against which a disk member 17 is positioned. the turned surface being formed with flats, (not shown) which are adapted to be engaged by 80 corresponding flat surfaces formed on the base of the disk. A washer 18 of predetermined thickness is next fitted on the turned surface, and a cutter 19 fits thereagainst, a washer and cutter being placed alternately 85 until the entire unit is assembled, when a disk 17^a is fitted on the opposite end. These cutters are formed with an uneven number of teeth 20 so that when assembled, the teeth of the adjacent cutters will alternate. 90

One end of the barrel is threaded as shown at 21, and a nut 22 is threaded thereon and serves to clamp the unit tightly in position.

The next step is the application of the abrasive material, this may be carborundum or a similar material, and is tightly wedged and packed in the interstices between the cutters until said interstices are completely filled, and the face of the abrasive material is flush with the face of the cutter teeth, these 100

cutters are of course hardened, and the body of the disk can be provided with small openings or laterally projecting wings to form a firm anchorage for the abrasive material.

5 The area of the abrasive material is of course determined by the thickness of the washers, and these can be made up in various thicknesses to suit the requirements.

I wish to direct particular attention to the 10 fact that the outer periphery of the end disks 17 and 17^a are smooth and are not provided with teeth, eliminating possibility of chipping or crumbling the abrasive material in the tool. The tool cuts as it grinds, so that 15 when the dressing is finished the grinding is also complete, the grinding speed being regulated by the number of the cutter teeth which must wear evenly with the abrasive material.

From the foregoing description it will be 20 obvious that I have perfected a very simple, economical, and effective combination cutting and grinding tool.

What I claim is:—

1. A combination dressing and grinding 25 tool comprising a plurality of spaced apart, hardened cutter disks, and an abrading material filling the interstices between said cutter disks.

2. A combination dressing and grinding 30 tool comprising a core adapted to be mounted on a shaft and having a plurality of spaced apart cutter members mounted thereon, and an abrading material filling the interstices between said members and flush with the outer periphery thereof.

3. A combination dressing and grinding 35 tool comprising a core having a plurality of spaced apart toothed cutter members, and an abrading material interposed between said cutter members and flush with the teeth of said cutters.

4. A combination dressing and grinding 40 tool comprising a core having a plurality of spaced apart toothed cutter members mounted thereon, and an abrading material between said members and flush with the teeth thereof, and means for clamping said cutters on the core.

5. A combination dressing and grinding 45 tool comprising a core having a plurality of spaced apart toothed cutter members mounted thereon to form a unit, disks on the ends of the cutter unit, and an abrading material interposed between said cutter members and forming a cylinder therewith.

6. A combination dressing and grinding 50 tool comprising a core, a plurality of spaced apart toothed cutter elements mounted thereon and forming a unit, smooth faced disks at the ends of the unit, and an abrading material between said elements and forming a smooth cylinder therewith.

In testimony whereof I hereunto affix my signature.

ROLAND P. PLACE.
